UNITED STATES PATENT OFFICE

2,387,310

FLOOR UNIT FOR REFRIGERATORS

Charles H. Walbert, Oklahoma City, Okla.

Application October 13, 1943, Serial No. 506,106

5 Claims. (Cl. 62—70)

This invention relates generally to the class of refrigeration and has to do particularly with refrigerators of the type employing ice as the refrigerating or chilling medium.

The present invention has for its principal object to provide a novel refrigerated floor unit for refrigerated structures such as domestic or commercial ice-boxes, refrigerator cars or the like, which is constructed to receive the drainage from the ice chamber so as to refrigerate the contents of the structure from the under side and also to obtain the maximum of chilling effect from the ice employed by introducing the ice-water resulting from the melting ice, under the material in the refrigerator.

Another object is to provide a removable floor unit for refrigerator food chambers or for other refrigerated structures, which is designed to receive the drippings from the ice chamber of the refrigerator so that there will be maintained a reservoir of cold water in the floor unit, upon which unit the food or other material which is to be kept refrigerated, is placed.

Other advantages will become apparent as the description of the invention proceeds and the invention will be best understood from a consideration of the following detailed description taken in connection with the accompanying drawings, it being understood that minor changes or modifications may be made in the structure so long as such changes or modifications are within the scope of the appended claims.

In the drawings:

Figure 1 is a view partly in section and partly in elevation of the lower front part of a refrigerator showing the refrigerated floor unit embodying the present invention, in position within the food chamber, a portion of the structure being in section.

Figure 2 is central vertical section through the lower part of the refrigerator structure and the refrigerated floor unit therein.

Figure 3 is a conventional illustration in perspective of an end of a refrigerator car with the side removed, showing the installation therein of a pair of refrigerated floor units constructed in accordance with the present invention.

Referring now more particularly to the drawings there is shown in Figure 1 the lower portion of a domestic ice-box or refrigerator in connection with which the present invention is shown. This domestic structure is generally indicated by the reference character R, the food chamber thereof being indicated at 10 and the front door leading into the food chamber by the numeral 11.

The numeral 12 designates a unit leading down into the back part of the food chamber from the upper compartment of the refrigerator in which the ice is placed, which unit is fully described in my copending application Ser. No. 506,105, filed Oct. 13, 1943, directed to a refrigeration structure, and comprises a vertical ice chamber in which ice in a finely broken up or divided form is placed and through which the drippings from the melting ice pass downwardly to be discharged through the open bottom 13. It is not believed that any further or more detailed description of this unit 12 is necessary in the present application as such unit is fully illustrated and described in my other application above identified and is merely shown to disclose one means for conducting drippings from melting ice in the upper ice chamber, into the floor unit constituting the present invention. Such drippings might be carried from the upper 10 ice chamber into the floor unit by the ordinary and well known drainage tube which commonly is found in ice refrigerators for conducting the drainage from the upper ice chamber downwardly to a discharge outlet leading from the lower part 20 of the food compartment and it is therefore to be understood that the present invention is not to be confined to the use of an ice-water supply means such as is shown but may be used in association with any structure where ice is used for refrigerating purposes and from which drainage water may be taken.

In accordance with the present invention there is provided a relatively shallow receptacle, indicated generally by the numeral 14, which comprises the bottom wall 15, top wall 16, front, side and back walls designated respectively 17, 18 and 19. At the back the wall 19 and the adjacent portions of the side walls 18 are extended upwardly to a substantial height above the top wall 16 and in cooperation with these walls there is an upwardly extending wall 20 spaced from the back wall 19 and joining the top wall 16, to form a well 21. This well 21 extends across the full width of the back part of the receptacle 14 and in effect forms an open top, upward extension of the back part of the receptacle which, when the receptacle is in place in the bottom of the food chamber 10, resting upon the floor of the food chamber, is in proper position at the back of the food chamber to receive drippings from the overlying unit 12 or from any other conducting means leading downwardly from the ice compartment of the refrigerator.

The portion of the receptacle forwardly of the well 21 is, as previously stated, relatively shallow

and forms a hollow floor unit resting upon the main floor of the food chamber, upon which bodies of food may be placed, the same, of course, resting upon the top wall 16.

Disposed within the shallow portion of the receptacle 14, that is, forwardly of the well 21, is a plurality of metal fins 22 which are secured to the top wall 16 and extend downwardly to relatively closely spaced relation with the bottom wall 15. These fins serve as conductors to effect transfer of heat between the contents of the food chamber and the ice-water with which the receptacle is filled.

Supported in a suitable manner in the upper part of the well 21 are filter units each of which is generally designated U and which comprise flat trays having the upstanding side walls 23 and perforated bottom walls 24. Supported in spaced relation with the bottom walls 24 is, in each tray, a perforated cover plate 25 and between each cover-plate and the bottom 24 is packed a suitable filter material such as charcoal or the like, indicated at 26. The melted water from the ice drips into these trays and passes through the charcoal, or other filtering means, into the receptacle and in this way there is prevented the development within the receptacle of scum such as is commonly found in ice-water chambers.

Any suitable means may be provided for draining the contents of the floor unit such as the rotary plug valve generally designated 27, having an actuating or control stem 28 extending upwardly through the receptacle and between the filter trays so that the plug of the valve may be conveniently reached to be turned to drain position. This valve may, if desired, be of the specially designed form disclosed in my co-pending application, by means of which automatic intermittent siphon draining of the receptacle is effected.

In Figure 3 there is illustrated the application of the refrigerated floor unit to a car structure such as a refrigerated car which is commonly employed for transporting fruit, meats or other food stuffs which must be kept at a low temperature. In this application, the car which is generally designated 29 has the cold water receptacle disposed upon the floor of the car in such a position that the well of the receptacle will be disposed beneath the drain outlet for the car ice bunker which is generally designated by the reference numeral 30. A customary arrangement of such bunkers in a refrigerator car is one at each end of the car and therefore in an arrangement of this kind the receptacle or refrigerated floor unit which is generally indicated by the reference character 14, is used in duplicate so that the ends remote from the well 21 will be in end opposed abutting relation and the well of each floor unit will be properly disposed at the end of the car beneath the bunker to receive the ice-water from the bunker. Except for the fact that the units used in the refrigerator car are of larger dimensions so as to completely cover the floor of the car they are exactly the same in construction as the unit designed for use in a domestic or commercial type of ice-box, each having a filter means in the upper part of the well and a drain means by which the contents of the receptacle may be run off when and as necessary.

While, as previously stated, the drain valve 27 here illustrated forms the subject matter of a separate application for patent, Ser. No. 506,104,

filed October 13, 1943, it might here be stated that its design is such as to enable it to perform a particularly desirable function when used in a unit of the character here disclosed, in association with the filter units U. It will be noted that this particular drainage means comprises a siphon tube 27', and a vertically disposed overflow or drain tube 27''. This siphon tube 27' is designed to start functioning for the drainage of water from the well, when the level of the water rises to the top of the tube. The stand pipe 27'' has its upper end at an elevation above the bend of the siphon tube so that the water does not flow off through this stand tube unless the siphon tube fails to function as, for example, if it should become plugged. Accordingly the tube 27'' seldom functions to carry off water from the well but it does function to admit air into the upper part of the well from the outside of the refrigerator structure so as to prevent the possibility of a vacuum being produced between the filter unit and the interior of the well. The stand tube 27'' also functions to carry off gases which may form in the well.

It will be seen upon reference to Figure 3 that the well of the floor unit as constructed for use in a refrigerator car will be disposed below the narrow lower portion of the ice bunker at the adjacent end of the car so as to receive drainage from within the bunker and also to receive moisture formed upon the outer side of the bunker by condensation as such moisture will run down the outer surface of the bunker and drip from the lower part thereof into the filter unit which is mounted in the top of the well.

In refrigerators having circular cabinets the cold water reservoir may be built in circular form with the well and siphon drain in the center and the reservoir may be supported to revolve so as to function as a revolving food shelf. This could be accomplished without alteration of the essential features of the invention.

I claim:

1. In a refrigerated structure having a food compartment and an ice chamber in the upper part thereof and having drainage means, a relatively shallow hollow floor unit adapted to be placed within the food compartment to rest upon the floor of such compartment, said floor unit having an upstanding open top well, the well being arranged to receive water from the drainage means, and a filtering unit supported in and closing the top of said well.

2. In a refrigerated structure having a food compartment and an ice chamber in the upper part thereof and having drainage means, a relatively shallow hollow floor unit adapted to be placed within the food compartment to rest upon the floor of such compartment, said floor unit having an upstanding open top well, the well being arranged to receive water from the drainage means, a drainage means for the floor unit, located within the well to maintain a predetermined water level therein, and a filter unit formed to position within the top of the well to close the latter, the filter unit being maintained at an elevation above the water level.

3. In a refrigerated structure having a food compartment and an ice-chamber in the upper part thereof and having drainage means, a relatively shallow hollow floor unit adapted to position within the food compartment to rest upon and cover substantially the entire area of the bottom of the compartment, said floor unit including an upstanding portion extending across

the rear and open at its top to form a well, the well being arranged to receive drainage from the drainage means, the floor unit having a top wall upon which may be placed material to be refrigerated, a plurality of fins integral with the underside of said top wall and suspended therefrom within the floor unit and spaced from the bottom of the unit, drainage means leading from the well and constructed and arranged to maintain a water level in the well above said top wall of the unit, and a filter closing the top of the well and maintained at an elevation above said water level.

4. In a refrigerated structure having a food compartment, an ice chamber in the upper part thereof and having drainage means, a relatively shallow hollow floor unit formed to position within the food compartment upon the floor of the food compartment, said hollow floor unit having a bottom wall and a top wall extending over and in spaced parallel relation with the major portion of the bottom wall, the floor unit including side and back walls, a well forming upward extensions of the top, side and back walls and having an open top, the open top of the well being positioned to receive drainage from the ice compartment, a drainage means for the floor

unit constructed and arranged to maintain a predetermined water level in the well above said top wall, a flat filter unit formed to fit within and close the top of the well, and means within the well for maintaining the filter unit at an elevation therein above the water level.

5. In a refrigerator car structure having an ice bunker across each end of the car, each bunker having downwardly discharging drainage means, a pair of relatively shallow hollow floor units adapted to be placed within the car upon the car floor to cover the latter, each of said floor units having a bottom wall and a top wall extending over and in spaced parallel relation with the major portion of the bottom wall and side and back walls, a well forming upward extensions of the top, side and back walls and having an open top, the units being disposed upon the car floor with the well of each unit beneath the drainage discharge means for a bunker, drainage means for each well constructed and arranged to maintain a predetermined water level therein, and a flat filter unit supported within and closing the top of each well, each filter unit being maintained at a level above the water level in the well.

CHARLES H. WALBERT.
